ROCKER BLADE BIT

Clyde E. Bannister, Akron, Ohio

Application November 14, 1933, Serial No. 697,883

12 Claims. (Cl. 255—61)

This invention relates to rotative bits and is of especial value for earth-boring bits of the oscillating type.

The chief objects of the invention are to provide a bit adapted to cut with high effectiveness in both directions of rotation, to provide economy of manufacture, to provide for convenient and economical repair of a dulled or broken bit, to provide a bit adapted to function effectively for long periods of time without interruption for sharpening or for repairs and, more specifically, to provide a self-sharpening bit.

Of the accompanying drawings:

Fig. 1 is a side elevation of one embodiment of my invention.

Fig. 2 is a bottom plan view of the same.

Fig. 3 is a vertical sectional view on the line 3—3 of Fig. 2.

Fig. 4 is a cross-sectional view on the line 4—4 of Fig. 3.

Fig. 5 is a side elevation of another embodiment of my invention.

Fig. 6 is a bottom plan view of the same.

Fig. 7 is a vertical sectional view on the line 7—7 of Fig. 6.

Fig. 8 is a cross-sectional view on the line 8—8 of Fig. 7.

Fig. 9 is a bottom plan view of a modification having staggered blades.

Fig. 10 is a cross-sectional view illustrating a reversible tapered blade.

Fig. 11 is a cross-sectional view illustrating a toothed blade, the blade-holding recess having provision to permit rocking or pivoting of said blade therein.

Fig. 12 is a perspective view of the toothed blade illustrated in section in Fig. 11.

Fig. 13 is an elevation of a bit equipped with blades such as that of Figs. 11 and 12.

Fig. 14 is a vertical section of the same.

Referring now to the drawings for a particular description of my invention, I designate generally a bit, having a reduced neck 2 and external threaded portion 3 adapted for attachment to and detachment from a suitable spindle or check.

This bit 1 has a conical portion 4 terminating in a point 5. Mounted within the conical portion 4 are a plurality of blades 7, each of these blades having a reduced upper portion 8 of less thickness than the width of the recess 6. A shaft 9 passes through the center of each blade, said shaft seating in a recess 10 at one end of the groove 6 and passing through an aperture 11 in the side of the bit 1.

The groove 6 is flared at its lower end as at 12,

being wider at this flaring portion than the thickness of the flared or widened portion 13 of the blade 7. Thus, as clearly illustrated in Fig. 4, the blade 7 is free to rock or pivot on the shaft 9 within the limits permitted by the walls of the groove 6 and the flared walls 12.

Each shaft 9 has a projecting end 16, and through this projecting end 16 and into the bit 1 is threaded a screw 17 or other retaining element to prevent endwise movement of the shaft 9 until it is desired to remove the same.

Each blade 7 is provided with two cutting edges, 14 and 15. Thus when the bit is oscillated to the left, Fig. 1, the cutting edge 14 will be presented to the formation being cut, and the blade 7 will rock or pivot on the shaft 9 until the cutting edge 14 is presented to the formation to be cut at the most efficient cutting angle. When the bit 1 oscillates in the opposite direction, or to the right, Fig. 1, the cutting edge 15 will be presented to the formation being cut, and the blade 7 will again rock or pivot on the shaft 9 until the blade 15 is presented at the best and most efficient cutting angle. Thus two separate and distinct cutting edges are provided on each blade, doubling the life and efficiency of these blades and increasing the speed of the work accomplished.

When it is desired to remove a blade 7 because of wear, breakage, or for other reasons, the screw 17 is removed, the shaft 9 withdrawn from the recess 10, through the blade 7, and aperture 11, whereupon the blade 7 will drop from its groove 6 and may be readily replaced with another blade, the shaft 9 then being replaced through the recess 10, new blade 7, and into the recess 10, whereupon the screw 17 is replaced and the bit is again ready for operation. This is a simple procedure and requires but a short space of time to effect these changes.

In order to provide for suitable flushing of the blades and of the bore in which they are operating, I form my novel bit partially hollow, as illustrated at 18, and through the solid portion of the bit I form fluid conducting apertures 19, three of these apertures being illustrated herein, although it will be appreciated that I may utilize any desirable number of same. The outlets of these apertures are preferably located closely adjacent to the blades 7 in order to insure that the blades will be kept well flushed, as well as flushing the cuttings of the blade from the bore in which they are operating.

Each of the blades is inclined, because of the conical portion 4 of the bit 1, and each blade is 55

angularly disposed with relation to the adjacent blades. Thus an extremely efficient type of bit is produced, particularly adapted for cutting through hard formations.

5 It will thus be instantly apparent to those skilled in this art that I have devised an entirely novel bit, one having great efficiency and possessing many advantageous features not heretofore found in existing bits. Each blade 7 projects

10 beyond the periphery of the bit 1, thus insuring a complete cutting of the bore without offering any resistance to the downward passage of the bit as it follows the blades in their downward path in the bore-cutting operation.

15 Each blade 7 is slightly V-shaped, as clearly illustrated, to provide the cutting edges 14 and 15. These blades 7 are easily re-sharpened and will have long life due to their novel and rugged structure.

20 The threaded portion 3 will, of course, be locked to the corresponding threaded portion of the spindle to which the bit is attached, thus preventing twisting off of the bit from the spindle during oscillatory movement of the bit. This locking can be effected in any desirable, suitable, or convenient manner.

25 Referring now to the embodiment shown in Figs. 5, 6, 7 and 8, 101 designates generally a bit having a reduced and threaded neck 102 and a conical head 103. Arranged at predetermined intervals around the periphery of the bit 101 are a plurality of vertical ribs 104. Inclined recesses 105 are provided extending through the ribs 104, partially through the bit 101 and to the center of the head 103. Positioned in each of these recesses 105 is a cutting element or blade 106 having a cutting portion 107 and a cutting portion 108, each portion 107 and 108 being provided with a plurality of cutting edges. These blades 106 are removably attached to the bit by rivets 109, one of said rivets extending through each rib 104. Flushing fluid exhaust outlets 110 are provided extending through the bit and terminating in the conical heads 103, each of said outlets being positioned between two of the cutting blades, although this arrangement and number of fluid outlets is optional.

30 Because of the reversability of the blades 106, when one portion, such as 107 for example, has become dulled through use, or has been broken and it is desired to reverse the blade, it is a simple matter to remove the rivets or bolts 109, withdraw the blades 106, reverse the same so that a new cutting portion, such as 108, will be in exposed or cutting position, replace the rivets or bolts 109, and the bit is again ready for operation.

35 Each blade 106 is inclined, and is angularly disposed with relation to the other blades of the bit, and each blade 106 extends beyond the outer edge of the ribs 104 so that the blades will cut a bore of greater diameter than the diameter of the bit. Thus the bit will meet with no resistance by the walls of the bore in its downward passage.

40 The blades 106 are not only removable and reversible, but are also interchangeable with any of the other blades in a bit, or with the blades in other bits.

45 This novel bit is possessed of many advantageous features, such as strength, durability, ruggedness, efficiency, quick-cutting capacity, length of life, as well as the reversability and interchangeability above briefly described.

50 In Fig. 9 I have illustrated a modification

5 wherein the bit 112 has a conical head 113 and vertical ribs 115, the recesses or grooves 114 being provided in both the head 113 and rib 115. These recesses, as well as the blades 116 positioned therein, are staggered and this form or arrangement of blades will be found advantageous in cutting through or boring certain formations. Each blade 115 is fixed to the ribs 115 and bit 112 by rivets or bolts 117.

55 Flushing fluid exhaust outlets 118 are provided for flushing the blades and for flushing the cuttings of the blades out of the bore, the blades 116 being reversible, removable, and interchangeable in the same manner as the blades 106. With these staggered blades, however, they cannot be inserted longitudinally of the grooves, but must be inserted laterally thereof.

60 In Fig. 10 I have illustrated another modification of the blade 106 of Figs. 5 to 8 inclusive. In this modification of the bit, the blade 120 is 20 tapered, as at 121 and 122, the groove 123 being correspondingly tapered. This blade 120 is reversible and interchangeable, but must be removed or withdrawn longitudinally of the groove 123, instead of merely dropped therefrom as in 25 removing the blade 106. This tapered blade 120 insures a strong firm holding of the blade in the groove, rivets or bolts being utilized to further insure this holding of the blade.

65 In Figs. 11, 12, 13 and 14 is illustrated a still further type of reversible blade 125, having tapered cutting portions 126 and 127. A central longitudinal projection 128, preferably rounded, is provided which acts as a pivot. This blade 125 is adapted to be inserted longitudinally into a 35 groove 133 in the bit 134, this groove being of a size to snugly receive the pivot portion 128 of the blade 125, but the upper and lower portions of the groove 133 being of a greater size than the portions 126 and 127 of the blade 125. This permits a rocking or pivoting of the blade 125 through a slight angle. Each portion 126 and 127 is provided with alternately arranged teeth 129, 129, and 130, 130. The cutting edges 131 of the teeth 129 are all on one side or edge, and the cutting edges 132 of the teeth 130 are all on the other side, thus affording two cutting edges on each portion 126 and 127.

70 Thus, when the bit 134 is oscillated in one direction, the cutting edge on one side of the exposed portion 127 of the blade 125 will dig in, while the other cutting edge will dig in while the bit is going in the opposite direction, the rocking or pivoting of the blade 125 presenting these cutting edges at the best and most efficient cutting angle. This blade 125 is likewise reversible, removable, and interchangeable, thus possessing all of the advantages of the blades above described.

75 The threaded portion 102 will, of course, be locked to the threaded spindle to which it is attached. This locking may be effected in any desired or convenient manner, many methods and means of thread-locking being well-known and it not being deemed necessary to illustrate the same in the present application.

80 This form of bit provides a self-sharpening feature, as adjacent teeth at the leading side of the bit leave between them a ridge of material 70 in contact with which the intervening, oppositely-facing tooth is dragged backward, with resulting wear of its bevel face and sharpening of its cutting edge.

85 Various further modifications are possible 75

within the scope of my invention as defined in the appended claims.

I claim:

1. A bit of the kind described, having a conical lower portion and having a plurality of inclined converging recesses formed in the conical portion thereof terminating at a substantially common center, a shaft passing through each of said recesses, a blade pivotally mounted on each of said shafts, and means to limit the pivotal movement of each blade.
2. A bit of the kind described, having a conical lower portion and having a plurality of converging recesses formed in the conical portion thereof terminating at a substantially common center, a shaft passing through each of said recesses and fixed at one end to said bit, a blade pivotally mounted on each of said shafts, and means to limit the pivotal movement of each blade.
3. A bit of the kind described, having a conical lower portion and having a plurality of converging recesses formed in the conical portion thereof terminating at a substantially common center, a shaft passing through each of said recesses and fixed at one end to said bit, a blade pivotally mounted on each of said shafts, and means to limit the pivotal movement of each blade, each of said blades having a plurality of cutting edges.
4. In an oscillating bit of the kind described, a pivoted cutting blade having a plurality of cutting edges adapted to effect an equal cutting action in different directions, oscillation of said bit automatically rocking said blade and presenting one of said cutting edges to the material to be cut, and means to limit the rocking movement of said blade.
5. In a bit of the kind described, a plurality of inclined divergently located cutting blades, angularly disposed with relation to each other and pivotally mounted on said bit, each blade having a plurality of cutting edges adapted to effect an equal cutting action in different directions, and means to limit the pivotal movement of said blades.
6. A bit of the kind described, having a conical lower portion and having a plurality of inclined

converging recesses formed in the conical portion thereof and terminating at a substantially common center, a blade pivotally mounted in each of said recesses, each of said blades having a reduced portion housed in its recess within the bit to limit the pivotal movement of the blade.

7. The combination with a bit of the kind described, of a plurality of reversible blades, each blade having two cutting portions, and each cutting portion having on one side of the bit's axis a plurality of teeth alternately facing in opposite directions.

8. The combination with a bit of the kind described, of a plurality of reversible blades, each blade having two cutting portions, and each cutting portion having on one side of the bit's axis a plurality of teeth alternately facing in opposite directions, on each cutting portion, said blades being pivotally mounted in said bit.

9. A bit of the kind described having a head formed with a plurality of grooves therein, a plurality of reversible blades pivotally mounted in said grooves, and a projection medially disposed on each side of each blade and extending longitudinally thereof and forming a pivot.

10. A bit of the kind described having a head formed with a groove in its lower face, a blade pivotally mounted in said groove, and a projection medially disposed on each side of the blade and extending longitudinally thereof and forming the pivot of the blade, said groove being of greater size than said blade to permit rocking of said blade through a predetermined angle.

11. A bit of the kind described having a head formed with a plurality of grooves therein terminating at a substantially common center, and a plurality of blades pivotally mounted in said grooves, each of said blades having two oppositely disposed cutting edges, said bit having a fluid outlet located between adjacent blades.

12. In a rotative bit, a cutter member formed on one side of the axis of the bit with a series of staggered cutting edges facing alternately in opposite directions.

CLYDE E. BANNISTER.
